UNITED STATES PATENT OFFICE.

IRVING C. JENNINGS, OF SOUTH NORWALK, CONNECTICUT.

HYDROTURBINE PUMP.

Application filed April 17, 1928. Serial No. 270,776.

The object of this invention is to improve the hydro-turbine pump shown in patent granted to Lewis H. Nash, No. 953,222, March 29, 1910. The pump shown in this 5 patent comprises an elliptical casing in which is arranged a circular rotor having a series of displacement chambers. Liquid is placed in the pump casing and the rotor is driven at high speed. The liquid in the casing will 10 travel around with the rotor and by centrifugal action will follow the outline of the casing.

By this arrangement the liquid will be forced into and out of the displacement chambers as the rotor turns. Suitable ports are provided so that the piston action of the liquid thus obtained can be utilized either to exhaust or compress a fluid.

In the construction shown in said patent, 20 the rotor is journaled on a hub or hubs and is provided with holes or ports extending from the bottom of the displacement chambers to cooperate with holes or ports formed in said hub or hubs. This arrangement is 25 advantageous in that the displacement chambers can be brought down nearly to the center of the rotor and thus a great proportion of the rotor space utilized; but it is disadvantageous in that it is difficult to maintain a tight fit 30 between the rotor and the hub or hubs.

The object of the present invention is to retain the advantage of said structure and do away with said disadvantage.

To accomplish this end the hub or hubs 35 on which the rotor turns is or are tapered and means are provided whereby adjustment can be made to keep the rotor tight thereon.

The improved structure is illustrated in 40 the accompanying two sheets of drawings, in which

Figure 1 is a central longitudinal section of a pump constructed to embody my improvement;

Fig. 2 is a cross-sectional elevation on the 45 line 2—2 of Fig. 1;

Fig. 3 is a cross-sectional elevation on the line 3—3 of Fig. 1; and

Fig. 4 is a partial longitudinal section 50 similar to Fig. 1, illustrating a modified construction.

Referring to the first three figures of the drawings, and in detail, A designates the pump casing and B designates a head or auxiliary casing. C designates the rotor

which is keyed on a driving shaft D, which is 55 journaled in bearings carried by the casings A and B. The bearings 10—10 shown, are ball bearings, and the right hand ball bearing is arranged in a bushing 11 which is adjustably threaded into the bracket extending 60 from the pump casing A, so that the position of the driving shaft D and the rotor C carried thereby can be adjusted axially.

The casing A is provided with an entrance pipe or passage E and with an outlet pipe or 65 passage F. The pump casing A is divided by a partition G, as shown in Fig. 2. The rotor C is tapered to fit nicely on the hub H. The hub H is provided with inlet ports and passages H²—H² and with outlet passages and 70 ports H³—H³.

The rotor C is provided with vanes c whereby a series of displacement chambers is formed and two openings C'—C' are formed at the bottom of each displacement chamber. 75

The auxiliary casing B is divided by a partition G' arranged similarly to the partition G in the casing A. The inlet or entrance pipe or passage E is connected around to the compartment in the auxiliary casing B by a passage e and the outlet pipe or passage F is connected around to the compartment in the auxiliary head B by a passage f. The auxiliary head or casing B is provided with a hub H', tapered reversely to the hub H on the 85 casing A.

The rotor C also fits on this second hub H'. This second hub H' is also provided with inlet ports and passages H²—H² and outlet 90 passages H³—H³.

It will be seen that the rotor thus is fitted to turn on two oppositely tapered hubs.

Suitable shims S are arranged between the casings A and B. When wear occurs, one or more of these shims can be removed and the 95 casings thus brought closer together. This will draw the hubs into the rotor and will adjust the bearing surfaces. The rotor can be adjusted nicely relatively to the hubs, by turning the bushing 11.

In some cases, I contemplate using only one tapered hub for the rotor, and such construction is shown in Fig. 4. In this arrangement, when it is desired to adjust the relation between the rotor and the hub, all that is necessary is to adjust the rotor axially in the 105 casing.

The details and arrangements herein shown

and described may be greatly varied by a skilled mechanic without departing from the spirit of the invention.

Having thus fully described my invention, 5 what I desire to claim by United States Letters Patent is:

1. In a hydro-turbine pump, the combination of a casing having a tapered hub, ports formed in said hub, a rotor turning on said hub and having displacement chambers, and 10 holes or ports in the bottom of the chambers cooperating with the ports in the tapered hub.

2. In a hydro-turbine pump, the combination of a casing having a tapered hub, ports 15 formed in said hub, a rotor turning on said hub and having displacement chambers, holes or ports in the bottom of the chambers cooperating with the ports in the tapered hub, and means for adjusting the parts axially to take 20 up wear.

3. In a hydro-turbine pump, the combination of a casing having a tapered hub, a head or auxiliary casing having a reversely tapered hub, ports formed in said hubs, a rotor turn- 25 ing on said hubs and having displacement

chambers, and holes or ports in the bottom of the chambers cooperating with the ports in the hubs.

4. In a hydro-turbine pump, the combination of a casing having a tapered hub, a head or auxiliary casing having a reversely tapered hub, ports formed in said hubs, a rotor turning on said hubs and having displacement chambers, and holes or ports in the bottom of the chambers cooperating with the ports in the hubs, the casing and the head being arranged so that they can be set closer together to take up wear. 30 35

5. In a hydro-turbine pump, the combination of a casing having a tapered hub, ports 40 formed in said hub, a driving shaft extending through said hub, a rotor secured on said shaft and turning on said tapered hub and having displacement chambers cooperating with the ports in the hub, and means for 45 axially adjusting the driving shaft.

In testimony whereof I have hereunto affixed my signature.

IRVING C. JENNINGS.
